UNITED STATES PATENT OFFICE.

CATHERINE JANE DAVIS, OF PORTLAND, OREGON.

CURTAIN AND SHADE HOLDER.

Application filed October 10, 1921. Serial No. 506,548.

To all whom it may concern:

Be it known that I, CATHERINE JANE DAVIS, a citizen of the United States, residing at Portland, in the county of Multnomah 5 and State of Oregon, have invented a new and useful Curtain and Shade Holder, of which the following is a specification.

My invention relates to improvements in curtain and shade holders in which a telescope 10 scoping base is provided with a curtain and shade bracket on one side and with clamping jaws on the other side.

The objects of my invention are to furnish a mechanism which is strong and simple 15 in construction; which can be quickly detached from one window and attached to another; and in which the shade bracket is capable of adjustment on the base.

Further objects and advantages are to be 20 found in the construction and arrangement of parts as will be described hereinafter.

I attain these objects with the mechanism illustrated in the accompanying drawing, in which—

Fig. I is a plan view of the entire apparatus.

Fig. II is a front elevation of Fig. I.

Fig. III is an end elevation of Fig. I, showing the curtain bracket.

Fig. IV is a cross section through Fig. II along the line IV—IV.

Similar numerals refer to similar parts throughout the several views.

The telescoping base consists of two tubes 35 1 having their bent ends firmly connected by a metal strip which may be designated as jaw plate 2. Telescopingly mounted in these tubes are the rods (or tubes) 3, which also have their bent ends connected by a 40 jaw plate 4. By means of a threaded pipe 5 in the jaw plate 2 and a corresponding thumb screw 6 in the jaw plate 4, the jaw plates can be clamped to a window jamb 7 (dotted lines in Fig. I). The teeth 8 in both 45 jaw plates prevent involuntary disengagement.

The curtain bracket 9 is bent of wire and rigidly affixed to the rods 3. If the curtain pole 10 has a hole, as in Fig. I, the nose 50 11 on the curtain bracket can be used to good advantage.

The shade bracket 12 is a rectangularly bent metal plate, mounted for slidable adjustment on the tubes 1, and provided in one

leg with a bearing 13 for the pivotal pin 55 of the shade roller 14. The other leg, which rests with its broad surface directly on the tubes 1, has a thumb screw 15 in the center, and vertically projecting straps 16 looping around the upper and lower tubes 1. The 60 straps overlap each other at the back of the base, and are provided with screw holes for the thumb screw 15.

Loosening of the thumb screw permits the bracket to be shifted along the straight portion of the tubes, so that variations in the length of the shade roller can be taken care of.

Tightening of the thumb screw secures the bracket in place and imparts rigidity to the 70 otherwise weak members constituting the base.

Having thus described my invention it will be seen that my objects have been accomplished, and though I have shown the preferred form of construction, I reserve to myself the right to make minor changes providing I do not violate the spirit and principle of my invention.

I claim:

In a curtain and shade holder, a telescoping base comprising two parallel tubes, two rods slidably mounted in the tubes, a curtain bracket rigidly affixed to the rods, a shade bracket slidably attached to the tubes, 85 the terminals of said tubes being bent at right angles parallel to each other and opposite to the shade bracket, the terminals of said rods being bent at right angles parallel to each other and opposite to the curtain 90 bracket, a jaw attached to the terminals of said tubes, a jaw attached to the terminals of said rods, each jaw comprising a rectangular metal plate, the ends of said metal plate being rolled around the terminals of 95 tubes and rods respectively and constituting a rigid support for said tubes and rods, teeth stamped from the metal plates near the edge farthest from the telescoping base, a threaded pipe sleeve having one end attached 100 to the metal plate on the tubes, and a thumb screw passing through the metal plate on the rods and engaging the threads in said pipe sleeve.

Signed by me at Portland, Oregon, this 105 5th day of October, 1921.

CATHERINE JANE DAVIS.
